UNIPOD FOR OPTICAL INSTRUMENTS

Oswald Buchner, West New York, N. J.

Application June 11, 1946, Serial No. 676,015

1 Claim. (Cl. 248—216)

1

My invention relates to portable supports for observation or recording apparatus, particularly for optical instruments such as cameras, telescopes and so forth. More specifically, the invention is concerned with improvements in supporting devices adapted for outdoor use, of the type which may be secured to fence posts, telegraph poles, or other suitable structures conveniently available as a base.

It has already been proposed to provide a camera with a detachable unipod comprising a universal joint of the ball-and-socket type, and to taper and thread the remote end of the unipod in such a manner that it may be readily screwed into a wooden surface serving as a base. A set screw provided in the socket was to enable the operator to adjust his instrument in any desired position relative to the supporting surface, over an angle determined by the construction of the joint.

One disadvantage of the known device is the fact that the angle of adjustment is always substantially less than 180°, in any direction, since the ball must be enclosed beyond its greatest section in order to prevent it from dropping out of the socket. Also, the pressure which the point of the set screw may exert upon the convex ball surface may not be adequate to secure the apparatus in its selected position.

It is an object of my invention to provide a detachable support, for optical instruments or the like, which is to enable such instrument to be rotated into any desired azimuth and inclination over an angle of 360° in both directions.

It is another object of my invention to provide a support, of the type described, which may be readily disassembled into conveniently portable parts.

It is a further object of my invention to provide a support permitting free rotation of the instrument within a given horizontal, vertical or inclined plane.

Additional objects and features of my invention will subsequently appear as the description proceeds, reference being had to the accompanying drawing, in which—

Fig. 1 shows a supporting device in accordance with the invention, screwed horizontally into an upright post and carrying a telescope in inclined position.

Fig. 2 shows the transverse portion of the device.

Fig. 3 shows a cross section of the transverse portion of the device, together with a portion of the tapered shank secured thereto.

Fig. 4 shows the assembly of Fig. 3, in different relative position of the parts.

Fig. 5 shows the assembled device in vertical position, screwed into a horizontal plank surface.

As illustrated in the drawing, the supporting device according to the invention principally consists of the tapered shank 1 and the perforated transverse piece 2. The latter comprises a plurality of cylindrical bores 3, 4 and 5, of which the first two may be parallel to each other and the third one perpendicular thereto. The shank 1 has a threaded end portion 6, best shown in Fig. 5, which may be screwed into any conveniently accessible surface such as post 7, Fig. 1, or plank 8, Fig. 5. The piece 2 further contains two threaded holes 9 and 10, communicating respectively with the single bore 3 and with bores 4, 5, to receive the adjusting screws 11 and 12. Either of the transversely arranged bores 4 and 5 may accommodate the supporting rod 13 which may be an integral or detachable part of a telescope, such as outlined at 14, or of any other instrument associated with the device. The rod 13 may be provided with a terminal screw 15 to prevent it from sliding out of the member 2 during the adjustment of screw 12. The shank 1 may also be provided with a circumferential groove 16 and, spaced therefrom, an indentation 17 adapted to receive the tip of screw 11. Preferably, the bores 3, 4 and 5 are of equal diameter, and the screws 11 and 12 may likewise be interchangeable. As shown in the drawing, the top of shank 1 may be flush with the upper surface of the piece 2 in the assembled condition shown in Figs. 1, 3 and 5.

If it be desired to adjust the instrument to a plurality of horizontal and vertical angles, this can be readily accomplished by inserting the shank 1 into the bore 3 and the instrument rod 13 into the bore 5. In the position shown in Fig. 1, selection of the azimuth angle is done by means of screw 12 and adjustment of the angle of inclination by means of screw 11. If the supporting device is to be mounted vertically, as in Fig. 5, then the said angles may be determined in analogous manner.

Again, it may be desired to leave the angle of inclination fixed and turn the instrument horizontally, as for scanning the horizon, or else the observer may want to follow the course of, say, an airplane at a particular angle to a plane of reference. This may conveniently be achieved by keeping one of the screws, such as 12, fixed and letting the other, 11, slide loosely in the

groove 16 of shank 1. A similar groove, not shown, may be provided in the rod 13. If the relative position between the shank 1 and the piece 2 is not to be changed, the screw 11 may be made to engage notch 17 so as to keep both parts fixed with respect to one another.

By inserting the rod 13 into bore 4 of piece 2, the shank 1 can be adapted to serve as a longitudinal extension of that rod whereby the instrument may be raised above its normal position. It will also be noted that the transverse piece 2, if fastened to shank 1 by means of screw 11 co-operating with notch 17, will constitute a convenient handle by virtue of which the taper 6 may be readily screwed into its base.

While I have described and illustrated a particular embodiment, departures may be made from the precise construction and appearance thereof without exceeding the scope and spirit of my invention. Thus, by foregoing some of its adjustability, the device may be consolidated into a single piece substantially combining parts 1 and 2, screw 11 having been dispensed with. What I consider novel, and desire to protect by Letters Patent, is the following:

A support for optical instruments, comprising a post member having a tapered wood-screw thread at one end; a head member having three holes, two of said holes being at right angles to each other and having intersecting axes, the third hole being parallel to one of the others, said post member being rotatably fastened in said third hole of said head member, and fastening means whereby the instrument to be supported is held in one of said intersecting holes.

OSWALD BUEHNER.
